ROAD SWEEPER

William E. Grace, Dallas, Tex.

Application March 12, 1940, Serial No. 323,501

3 Claims.

(Cl. 15—82)

This invention relates to sweepers of the type having a rotatable brush and which are used for sweeping and cleaning road or street surfaces, and more particularly to that class that is trailed behind a truck or other moving vehicle to supply the power for pulling it forward. It is also a well known fact a sweeper of the class outlined herewith is very necessary for the summer maintenance of asphaltic surface treatment. The hot sun causes the asphalt to bleed or become sticky, and unless some excess gravel is kept on the surface, tires will pick up the sticky asphalt and greatly damage the road, thus it is very essential to throw the gravel which has been whipped by traffic into the gutter, back toward the center of the road.

The object of the invention is to provide a sweeper in which a rotary brush is employed, the brush being rotated by means of a chain drive which is connected to the rear axle of the machine by a sprocket. The power is transmitted to the brush through a transmission and a single universal joint. The universal joint is aligned along the axes of the king-pin around which the brush swings to change its sweeping angles, and is the improvement, over other types of sweepers, that I wish to protect by Letters Patent.

Another object of the invention is to secure, through the simpler construction as set forth, a more flexible control of the brush, permitting it to sweep right or left by adjusting it to the proper angle the change being made in a simple manner, in a few seconds of time and requiring the effort of only one man.

A still further object is to provide a sweeper which is simple, comparatively inexpensive, durable in construction, easy to operate, effective in use and with only three assemblies—the front wheel and arched box beam—the rear end with transmission and center kingpost—and the brush assembly which rotates about the kingpost. These are easily taken apart when it is desired to load the sweeper on a truck with other equipment for transportation.

Referring to the drawing in which:

Figure 1 is a side elevation.

Figure 2 is a plan view with dash lines indicating the angles to which the brush may be adjusted for sweeping right or left of roadway,

Figure 3 is a cross section taken on line 3—3 of Figure 2, and

Figure 4 is a detail plan view of transmission, showing gears for changing the direction of rotation of the brush.

In the drawing, in which like characters of

reference denote like parts throughout the several views, A represents a longitudinal arched box beam, the forward end being supported by a single wheel B, the rear end of this beam is forked and 5 the end of each prong of the fork C is welded or otherwise fastened to the bearings 1 of the axle 2. A cross member 3 completes the rear part of the frame. A brace beam 4 is fastened to the crossmember 3 and reaches forward, at right 10 angles to said crossmember, and supports the transmission 5. For additional strength, and support, a hanger 6 is provided, the upper end being fastened to one of the forked ends of the beam A. In the crotch of the fork C is located 15 and welded, forming a part thereof, the kingpost 7 to receive the kingpin 8. To the lower end of the kingpin 8 is securely fastened a crossbeam 9 which carries the brush assembly and the power shaft 10. The universal joint 11 is directly under and in line with the kingpin 8 thus permitting the brush D, and its assembled parts, to swing to right or left to any desired angle as indicated by the dashlines E. A sprocket 12 is carried on the axle 2 and transmits power to the chain 13 which 20 drives the sprocket 14 which is the input of the transmission 5. On the same shaft with sprocket 14 is a gear 15 that meshes with a gear 16 and reverses the direction of rotation of the shaft 10, which is the output of the transmission, 25 and reverses the direction of rotation of the brush, as indicated by the arrow F.

It should be noted that while only two gears are shown, for the purpose of reversing the direction of the brush's rotation, more gears may 35 be added, with suitable gearshift lever, for changing the speed also. The shaft 10 transmits power to the sprocket 17 and the chain 18, sprocket 19 and the brush shaft 20. The chain 18 is enclosed, for safety, by a guard cover 21. A pin 40 22 holds the brush in a locked position and is inserted in holes 23 when an angling adjustment is desired.

The lever 24 serves to raise and lower the brush, and the springs 25 to hold the brush in 45 proper contact with the road surface.

The pin 22 is used only when angles less than that shown by dashlines E are desired, a full angle, equaling that of the dashlines, is secured and held by the stops 26. It is one of the purposes of this invention to provide a machine that can be easily and quickly changed to sweep either right or left by one man, without removing bolts, pins or shifting levers. The brush is so located ahead of the center column that when moved to either right or left positions the cen-

ter of effort or the force necessary to push the brush is sufficiently to the right or left of said column to maintain the angle without the use of any additional locking devices. The stops 26 are provided, in this case, to prevent the brush from being turned at too great an angle.

In the construction of other sweeping devices that could be changed to sweep right or left, difficulty has been encountered with the power transmission shaft, two or more universal joints being used and a telescoping joint, or sliding sleeve, used in connection with the universal joints to provide for varying lengths of shaft necessary due to their inability to mount the universal joints in the same vertical plane at the center about which the brush was rotated. The telescoping joint has also been a source of trouble due to dust and sand entering and clogging and binding same.

The construction of my sweeper eliminates the telescoping joint, and employs only one universal joint, by mounting and rotating the brush around a central column, and supporting said column from the top and sides, sufficient clearance is provided under the column for positioning the single universal joint so that it is in proper alignment at all times, whether the brush is in right or left positions, and no sliding or telescoping action is necessary in any part of the shaft.

I do not desire to be understood as limiting myself to the specific details of construction and arrangement as herein described and illustrated, as it is manifest that variations and modifications may be made in the construction. I therefore reserve the right to all such variations and modifications as properly fall within the scope of my invention and the terms of the following claims.

What I claim as new is:

1. A road sweeping machine including a substantially V-shaped frame having a forward and a pair of rear supporting wheels, a kingpost supported at the intersection of the members of said frame, a kingpin rotatably mounted in said king-

post, a cross-beam carried by said kingpin, a rotary brush supported by said cross-beam, a power transmission supported from said frame rearwardly of said brush, means for transmitting 5 tractive power of said rear wheels to drive said transmission and a universal shaft for imparting rotary motion to said brush from said transmission.

2. A road sweeper comprising a frame mounted on wheels, a cross-beam, a kingpost supported by said frame, a rotary brush mounted on a shaft whose ends are supported by said cross-beam, a kingpin rising from said cross-beam at a point midway between its ends and receivable 10 rotatably in said kingpost to oscillatably support said brush, a power transmission, means for driving said transmission from the tractive power of the wheels of said frame, a universal joint actuated by said transmission and disposed in vertical alinement with the oscillative axis of said brush, a shaft connected to said universal joint, and means for imparting rotary motion to said brush from said shaft and means jointly carried by said kingpost and pin for holding said brush 15 against oscillation.

3. A road sweeper comprising a frame supported on wheels, a cross-beam carried by said frame, a brush mounted on a shaft whose ends are supported by said cross-beam, a kingpin vertically mounted midway between the ends of said cross-beam, a kingpost fixed to said frame and receiving said kingpin, means for holding said kingpin against rotative displacement from selected positions in said kingpost whereby to maintain said brush in fixed angular relation to a road, a power transmission, means for transmitting tractive power from the wheels of said frame to said transmission, a universal joint disposed in vertical alinement with said kingpin, a shaft connected to said universal joint and disposed parallel to the axis of said brush, means for rotating said brush from said shaft and means for raising and lowering said brush.

WILLIAM E. GRACE.
